CLAIM

The ornamental design for a recreational flotation device, as shown and described.

DESCRIPTION

FIG. 1 is a rear perspective view of a recreational flotation device in accordance with my new design.

FIG. 2 is a top plan view of the recreational flotation device.

FIG. 3 is an elevational view of the right side of the recreational flotation device of FIG. 2, the left side elevational view being a mirror image thereof.

FIG. 4 is an elevational view of the front of the recreational flotation device of FIG. 2.

FIG. 5 is an elevational view of the rear of the recreational flotation device of FIG. 2; and,

FIG. 6 is a bottom plan view of the recreational flotation device.
